Inventor:
Arthur F. Poole.

UNITED STATES PATENT OFFICE.

ARTHUR F. POOLE, OF KENILWORTH, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

LOCK FOR TOTALIZERS.

1,391,142.

Specification of Letters Patent. Patented Sept. 20, 1921.

Application filed February 21, 1920. Serial No. 360,362.

To all whom it may concern:

Be it known that I, ARTHUR F. POOLE, a citizen of the United States, residing at Kenilworth, in the county of Cook and State 5 of Illinois, have invented certain new and useful Improvements in Locks for Totalizers, of which the following is a specification.

My invention is an improvement in typewriter computing machines and is especially applicable to the Wahl adding machine, now extensively marketed by the Remington Typewriter Company, and which is thoroughly described in the issued patent to 15 John C. Wahl, No. 1,270,471, dated June 25, 1918.

The object of my invention is to provide a lock for the totalizer of a machine of the above type, to the end that accidental mis- 20 operation of the totalizer may be prevented.

Reference to the cited patent to Wahl, particularly to Figures 14 and 16 thereof, will disclose that the totalizer described in said patent consists of a series of gear wheels 25 adapted to be actuated *seriatim* by a master wheel.

In order to provide for the operation or carrying or accumulating of tens, each gear wheel is connected to a similar gear wheel 30 of next higher order by a Geneva gear, which has the function of advancing the wheel of higher order one step for each complete cycle of the wheel of lower order. In the Wahl machine described in the cited 35 patent, this cycle consists of ten steps.

In order to prevent overthrow, these intermediate gears in the Wahl machine are in the well known Geneva form, which includes suitable locking surfaces, to the end 40 that the wheel of higher order is locked against rotation except at the time when motion is communicated to it by a carrying step from the wheel of lower order, and for the further purpose of insuring that but one 45 step shall be made by the wheel of higher order at this time.

As so far described, the Wahl totalizer contains a chain of gear wheels which can be actuated only at the lowest wheel, since 50 all the wheels of higher order are locked except as they may be unlocked to be advanced during a carrying operation.

In order to provide for the insertion of numbers at various decimal places, the intermediate wheels of the Wahl totalizer just 55 referred to are mounted on certain swinging arms, which are adapted to be raised before a wheel is operated. Raising of these intermediate gears thus unlocks the chain of gears at the actuated point and there re- 60 mains a locked chain of gearing from the actuated point to the highest wheel of the totalizer, thus effectually preventing any overthrow in said higher wheels.

The swinging arms upon which the intermediate wheels are mounted are held in their normal position by spring pressure, and if force were applied to any wheel of the totalizer, then it is possible to rotate such a wheel, due to the fact that the intermediate 70 gears are forced out of mesh with their associated wheel, due to the yielding of the spring which serves to hold the swinging arm in its normal position.

It is the object of my present invention to 75 provide a lock, such that when the totalizer is out of the adding zone, that is, is out of a position to be actuated by the master wheel of the machine, the above described accidental rotation will be impossible.

My invention may be best understood by reference to the accompanying drawings, of which—

Fig. 1 is a sectional view of the totalizer including the locking mechanism peculiar to 85 my invention,

Fig. 2 is a top view of the same, and

Fig. 3 is a perspective view of certain details to be described hereafter.

While I have described my invention in 90 its preferred form as adapted to a Wahl totalizer, I do not wish to restrict my invention to this particular type, since it will be obvious to those skilled in the art that my invention will be useful in connection with 95 other totalizers in addition to the Wahl totalizer.

Referring to the figures, the totalizer contains in each decimal place a carrying wheel 10, which is rotatably mounted on a shaft 100 11, held between the totalizer side plates 12 and 13. Each carrying wheel 10 is connected by the transfer wheel 14 to the carrying wheel 10 of next higher order. Trans-

fer wheels 14 are rotatably mounted on the swinging arms 15, rotatably mounted on shafts 16 and 17 extending between the side plates 12 and 13 of the totalizer. Each of the swinging arms 15 is provided with an operating cam 18, which operates on a safety bar 19 rotatably mounted between the side plates 12 and 13 on a shaft 20. Each one of the swinging arms is provided with a locking surface 21 adapted to be engaged by a concentric cam surface 22 on the safety bar 19 which extends across the entire width of the totalizer and is adapted to engage any of the swinging arms 15. Upon any of the swinging arms 15 being actuated, the cam 18 will lift the safety bar 19, rotating it on its shaft 20, and the concentric surface 22 will engage the cams 21 on all of the balance of the swinging arms 15, thus preventing said arms from being raised out of mesh during the subsequent actuation of the gear wheels 10. This safety bar action has been very thoroughly described in the issued patent to Wahl and Goldberg, No. 896,871, dated August 25, 1908.

The object of the safety bar arrangement just described is to lock all the swinging arms 15 in their position, except the one, which has been raised to permit the actuation of the totalizer. It is obvious that the safety bar 19 will not prevent the simultaneous raising of more than one of the swinging arms 15, and it is this fact which permits one to rotate the wheels 10 when the totalizer is out of the adding zone.

All the mechanism just described is common to the totalizer described in the Wahl Patent No. 1,270,471. I will now describe the mechanism peculiar to my present invention:

Pivotaly mounted on the side plates 12 and 13 of the totalizer is a bail 23, one arm 24 of which is adapted to rotate on a stud screw 25 in the side plate 13. The other arm 26 of the bail is provided with a square hole 27 (Fig. 3) adapted to fit over a square 28 on a stud 29 rotatably mounted in the side plate 12. A screw 30 serves to hold the arm 26 on its seat 28 on the stud 29. Rigidly with the stud 29 is an arm 31 which extends on the inside of the totalizer and is held in engagement with the safety bar 19 by a spring 32 extending between the arm 31 and a stud 33 in the side plate 12. Thus the bail 27 will tend to rotate in a clockwise direction (Fig. 1) and thus rotate the safety bar 19, thereby bringing the concentric surface 22 in a position to lock the cams 21, thus preventing any of the swinging arms 15 from being raised. When the parts are in the above described condition, the totalizer as a whole is locked, since the wheel 10 of lowest order is locked by the units lock 34, which is mounted on an arm similar to the swinging arms 15 and all the wheels

of higher order are locked because of the presence of the Geneva gears 14. When the totalizer is in this condition it is impossible to rotate any of the wheels, either by accident or design.

To provide for the unlocking of the totalizer when the same comes into an operating zone, that is to say, when any of the wheels 10 are in engagement with a master wheel 35 which serves to insert numbers into the totalizer in the method described in the cited patent to Wahl, the bail 23 comes into operative engagement with a roller 36 mounted on the framework 37 of the adding machine. The bail 23 is provided with inclined surfaces 38 and 39, and a straight surface 40. The inclined surfaces 38 and 39 afford an easy engagement with the roller 36, and the straight surface 40 serves to maintain the bail 23 in an inoperative position, that is, it serves to maintain the bail in the position shown in Fig. 1 during the entire adding zone of the totalizer. When the roller 36 is engaged with the straight surface 40 of the bail 23, the normal operations of the totalizer are not interfered with, since the arm 31 is in the position shown in Fig. 1. However, as soon as the totalizer passes out of the adding zone, the bail 23 falls to a lower position, due to the action of the spring 32, thus rotating the safety bar 19 and locking all of the swinging arms, including the one carrying the units lock 34 in the position shown in Fig. 1. As pointed out, when the arms 15 are held or locked in the position shown in Fig. 1, it is impossible to rotate any of the wheels of the totalizer, and since the number wheels are geared to the wheels 10, the totalizer is completely locked. Since the number wheels 46 of the totalizer are geared to the wheels 10, it is impossible to insert any number whatever into the totalizer.

From the above it will be apparent that when a totalizer is out of the adding zone, all of the wheels will be locked and it will be impossible to insert a number therein by accident. However, as soon as the totalizer enters the actuating zone, the engagement of the bail 23 with the roller 36 will, by bringing the arm 31 to the position shown in Fig. 1, disable the lock.

It is apparent that the provision of this lock on the totalizer of the Wahl machine is entirely optional; that they will operate very well without the lock forming the subject of my present invention, but that this lock will afford an additional safe-guard against the totalizer being accidentally disturbed during the time when it is not in the operating zone.

Many improvements and variations may be made from the herein described mechanism without departing from the spirit of my invention, since I claim:

1. In combination, a traveling totalizer having totalizer wheels and having releasable means for locking said wheels, means for inserting numbers in said totalizer *seriatim*, and means actuated by the travel of said totalizer for operating said locking means to lock the wheels of said totalizer against accidental rotation outside a computing zone and to release said locking means in a computing zone. 55
2. In combination, a totalizer, a traveling carriage, means brought into operation by said traveling carriage to determine the decimal places in which numbers may be inserted in said totalizer, a releasable lock in said totalizer adapted to lock the wheels of said totalizer against accidental rotation and means controlled by said traveling carriage to govern the operation of said lock. 60
3. In combination, a totalizer, means for inserting numbers therein *seriatim*, a traveling carriage, a lock adapted to prevent the wheels of said totalizer from being accidentally rotated, and means operated by the travel of said carriage for shifting a part of said lock to effective and to ineffective positions. 65
4. In a calculating machine, the combination of a totalizer, means for inserting numbers therein, a traveling carriage, a locking bar in said totalizer, and means operated by the travel of the carriage for moving said bar to locking and unlocking positions. 70
5. In combination, a totalizer, a framework, means to cause said totalizer to travel relative to said framework, a cam on said totalizer, a lock for said totalizer wheels controlled by said cam, and means mounted on said framework and adapted to operate on said cam and determine the zone of operations thereof. 75
6. In a calculating machine, the combination of an actuator; a totalizer comprising a series of number wheels and means embodied in said totalizer for preventing accidental turning of any of said wheels when the totalizer is in non-operative position in said machine; and means outside of said totalizer for releasing said preventing means when the totalizer is in computing position, said totalizer and said releasing means having a relative traveling movement, to and from each other and said release of said preventive means operating automatically before said actuator operates. 80
7. In a calculating machine, the combination of a totalizer comprising a series of register wheels; transfer devices yieldingly engaging said register wheels; means for positively locking said transfer devices and thereby positively locking said register wheels; means for actuating said register wheels; a traveling carriage imparting a relative traveling movement between said totalizer and said actuating means; and means whereby the travel of said carriage operates said positive locking means to lock the register wheels when the totalizer and its actuator are out of coöperative position and to unlock said locking means when said totalizer and its actuating means are in coöperative position. 85
8. In a calculating machine, the combination of a totalizer comprising register wheels, transfer mechanism comprising Geneva wheels mounted for motion into and out of engagement with said register wheels, and means for positively locking said Geneva wheels in engagement; an actuator for said register wheels; a carriage imparting a relative traveling movement between said actuator and said totalizer whereby the totalizer is sometimes in coöperative relation to said actuator and sometimes out of such relation; and means actuated by the travel of the carriage for operating said locking means to positively lock the Geneva wheels in engagement when the totalizer and the actuator are out of coöperation and to unlock them when said totalizer and its actuator are in coöperation. 90
9. In a calculating machine, the combination of numeral keys; a totalizer comprising a series of number wheels and means embodied in said totalizer for preventing accidental turning of any of said wheels when the totalizer is in non-operative position in said machine, said means comprising the rocking bar 19, the spring-actuated lever 31, and the bail 23 on the totalizer; and an actuator 36 on the framework for operating said bail. 95

In witness whereof I have hereunto subscribed my name.

ARTHUR F. POOLE.
